REFRIGERATION

Frederic L. Chase, Dayton, Ohio, assignor to General Motors Corporation, Dayton, Ohio, a corporation of Delaware

Application August 31, 1935, Serial No. 38,800

19 Claims. (Cl. 62—170)

This invention relates to refrigeration and more particularly to a method of preparing the insulation of motor windings, leads, etc., for sealed units of refrigerating systems, and is a continuation in part of application No. 679,923, filed July 11, 1933.

Heretofore it has been customary to provide refrigerating systems with sealed units in which the motor and compressor are sealed in a hermetic casing. The electric motor has windings, leads, etc., which are generally covered with cotton and paper insulation. I have discovered that when such windings, leads, etc., are used in refrigerating systems in which certain circulating agents, such as highly solvent refrigerants and lubricants, are used, and also in which anti-freeze solutions such as alcohol are used, certain natural resins, waxes and oils of the cotton insulation are dissolved and are carried along throughout the refrigerating system by these agents. At places where there is a change of phase, or a decided change in temperature even without a change of phase, these natural resins are likely to be precipitated or deposited. If the passageway is of small dimensions, the accumulations of these resins, waxes and oils may eventually render the refrigerating system inoperative.

For example, in the type of refrigerating system where a relatively long capillary tube is used as the expansion member, and in which a sealed motor-compressor unit is used in which the motor windings, leads, binding tapes, etc., are allowed to come in contact with the circulating agents flowing through the system, and in which these circulating agents comprise a fluorine refrigerant, such as $C_2Cl_2F_4$, and lubricants such as mineral oils with or without the use of an anti-freeze medium such as alcohol, I have discovered that the natural resins, waxes and oils in the cotton insulation of the windings, leads, binding tapes, etc., and in paper used, are dissolved and eventually are deposited in the capillary tube, so that, after a short shut-down, such as for defrosting or the like, the capillary passageway is clogged and the system will not refrigerate again without an objectionable service operation.

I overcome these objections by removing substantially all of these natural resins, waxes and oils which are soluble in these agents from the cotton insulation prior to the sealing up of the refrigerating system, and preferably before any of the permanent circulating agents of the system are introduced therein. A suitable way of

removing these resins is to treat the cotton, either before or after it is assembled in the unit by dissolving and removing them with suitable solvents. For example the cotton is treated before the circulating agents are introduced, with an organic solvent or mixture or series of solvents, and, as one example, the cotton is treated with one or more non-polar solvents, such as toluol, zylol, naphtha or petroleum ether and with one or more polar solvents, such as methyl or ethyl alcohol, with a sufficiently thorough application and washing action to remove at least enough of these resins, waxes or oils to render them harmless in the system. Thereafter when the system is charged with its permanent circulating agents, the objectionable clogging will not occur.

If desired, the solvents may be purified after the washing operation and used again.

As it is also desirable to remove as much moisture as possible from the motor parts before charging the system with refrigerant, this removal of moisture conveniently may be accomplished simultaneously with one of the treatments above described.

As examples of specific methods and apparatus for practicing my invention, and not by way of limiting the scope of the invention, reference is made to the accompanying drawings for more detailed disclosure of the embodiments now preferred by me.

In the drawings:

Fig. 1 is a diagrammatic representation of a refrigerating system to which my invention may be applied;

Fig. 2 is a diagrammatic representation of a motor stator which may be used in the system shown in Fig. 1;

Fig. 3 is a diagrammatic representation of an apparatus which may be used for the treatment of motor parts either with the polar or non-polar solvents;

Fig. 4 is a diagrammatic representation of a different apparatus in which the motor parts may be treated with the polar solvent;

Fig. 5 is a diagrammatic representation of a modified form of apparatus for the treatment of motor parts with non-polar solvents; and

Fig. 6 is a transverse cross-sectional view of a portion of Fig. 4.

A refrigerating system to which my invention may be applied may include, for example, a motor-compressor unit 1, preferably of the hermetically sealed type in which both the motor and compressor are contained in a hermetic cas-

ing and in which the motor windings, leads, binding tapes, etc., are allowed to come in contact with the circulating agents flowing through the system. The unit 1 forwards the circulating agents, which may include a volatile refrigerant and lubricant with or without a small quantity of alcohol, as hereinbefore described, through the line 2 to a condenser 3 from whence liquid flows into the receiver 4. From thence the refrigerant and/or lubricant flows through the line 5, through an interchanger 5a to the expansion device 6, which may be of the elongated orifice or capillary passageway type from whence the refrigerant flows through the evaporator 7, where the refrigerant is evaporated and from whence it returns through the line 8 to the motor-compressor unit 1.

The motor of the unit 1 may have a stator which is diagrammatically illustrated in Fig. 2. 20 This stator includes windings 9 which may have cotton insulation around the individual wires, as is well known, and the windings may be held in place by binding tapes 10. The windings may be energized by current flowing through the leads 11, 12 and 13, which leads may have cotton insulation around them as is well known.

The cotton insulation of the motor windings and leads and the binding tapes, etc., may be treated with the solvent or solvents 14 contained in the tank 15, Fig. 3, in any suitable manner as by dipping them in the solvent or solvents.

The treating operation for the cotton may be performed either before the cotton is applied to the windings or after it is applied to the windings. 35 In fact, the stator shown in Fig. 2 may, itself, be submerged and washed in the tank 15. The motor rotor, if of the type requiring treatment may also be similarly treated.

The apparatus shown in Fig. 3 may be used to 40 treat the motor parts with polar or non-polar solvents, it being understood that preferably duplicate sets of apparatus as shown in Fig. 3 may be used, one for the treatment with the polar solvents and another with the treatment for the 45 non-polar solvents. The motor parts, such as the stator and/or rotor are introduced into the kettle 15 which is thereafter sealed. The valves 28 and 21 are closed and the solvent supply valve 22 is opened, thus introducing a quantity of solvent 50 into the kettle 15 sufficient to submerge the motor parts. Thereafter the valve 22 is closed and the burner 23 is ignited to heat the kettle under the control of the thermostatic valve 24 which is 55 throttled by the bulb 25 to maintain the desired temperature of solvent. The solvent vapors and/or water vapors are driven off through the pipe 26 to the reflux condenser 27, cooled by the pipe 28 through which water or other cooling medium may be circulated. The condensate is 60 gathered in the sight glass 29 where its character may be inspected. Periodically the condensate may be emptied by opening the valves 21 and 26 so that the condensate and the solvent remaining 65 in the tank 15 may drain into the still 38 for purification of the solvent. A sufficient supply of solvent is maintained in the kettle to submerge the motor parts during the treatment.

The solvent, together with the impurities, with 70 or without water is then heated in the still 38 by igniting the burner 31 under the control of valve 32 which in turn is controlled by the thermostatic bulb 33. The vapors are driven off through the pipe 34 to the condenser 35, cooled by water circulating through pipe 36. The purified solvent drains through the pipe 37 into the

receptacle 38 from which it may be removed for reuse, any water present being decanted, or otherwise removed from the solvent.

In the treatment shown in Figs. 4 and 5, the treatment with a polar solvent may be accomplished in a washer of the type diagrammatically depicted in Fig. 4, while the treatment with the non-polar solvent may be accomplished in an apparatus of the type diagrammatically shown in Fig. 5. 10

The treatment with a polar solvent may be accomplished in any suitable washing machine. For example, as shown in Fig. 4, the stators or rotors are mounted on spindles 160, the stators or rotors being indicated at 161. These spindles 15 are mounted on a suitable rotating structure 162 which also rotates the spindles and gives them a rotary motion. The motor parts are thus dipped, while rotating, in a body 163 of polar solvent, such as methyl or ethyl alcohol. The alcohol is heated by steam jacket or the like 164. The alcohol vapors from this treatment may be condensed, in a reflux condenser 164a and the alcohol may be further purified, if necessary, for 25 reuse.

The stators and/or rotors may also be given the treatment with the non-polar solvent. This may be accomplished in an apparatus as shown in Fig. 5. The stators and/or rotors are placed in a steam jacketed kettle 165, preferably in a basket 166 which holds the stators above the bottom of the kettle as indicated. The jacket 167 may be supplied with steam for heating purposes through the pipe 168 having valve 169. A suitable sight glass 170 may also be provided in the kettle. The vapor space of the kettle is connected by a pipe 171 with a reflux condenser 172. A pipe 173 leads to a vent line 174 open to the atmosphere and which is provided with a valve 175 and a sight glass 176 having a drain with valve 40 178a. The pipe 173 is also connected with a pipe 177 leading to a vacuum pump 177a and provided with a valve 178 and a pressure gauge 179. The reflux condenser drains through a pipe 179 and valve 181 to a reflux sight glass 172. This sight glass drains through the valved drain 173 into the sump tank 174 which in turn is provided with a valved drain 175. The steam jacketed kettle 165 is connected by the pipe 179 with a manifold 171 which in turn is connected with valves and pipes 178, 179, 180 and 181 which are connected respectively with an oil sump, an oil supply, a solvent supply and a solvent sump. 50

When the stators or rotors are ready to be treated, they are placed in the basket 166 while the steam jacketed kettle is being heated by steam. At this stage, the vacuum valve 178 is closed and the vent valve 175 is opened. The kettle is sealed tightly and the valves 178, 179, 180 and 181 are closed. The valve 178 is opened 60 admitting a non-polar solvent, such as toluol, until it is slightly above the bottom of the stator basket. The toluol is allowed to boil while being heated by the steam in the jacket until its level is below the stator basket, thus driving off the air in the system. Thereafter the vent valve 175 is closed and the vacuum valve 178 opened and a vacuum of approximately 28 inches mercury is imposed on the kettle. A slight amount of toluol is then added by opening valve 178 until the vacuum drops to 25 inches mercury, all the time allowing the toluol to boil so that the hot toluol vapors come in contact with the stators. The hot toluol vapors drive off a large amount of moisture from the stators. During this time 70 75

the valve 121 is opened and the valve 123, which is maintained normally closed, is intermittently opened to drain the toluol from the water in the sight glass 122. This procedure is repeated 5 introducing toluol into the lower part of the kettle and boiling it off until the toluol which drains into the sight glass 122 appears clear, thus indicating that a large amount of the moisture has been driven off the motor parts. After no substantial 10 moisture is further driven off by toluol vapor, the vacuum valve 115 is closed and toluol is introduced until it submerges the stators. When the pressure has risen sufficiently, the vent valve 115 is opened and the toluol is boiled for 30 minutes causing the toluol to dissolve the undesirable constituents in the windings. The toluol is then drained from the kettle for approximately 15 minutes after which the stators are again subjected to hot toluol vapors under vacuum to remove any slight traces of moisture remaining. After the kettle has been subjected to a vacuum while the stators are being treated to toluol vapors the second time, and after this last treatment is completed, oil is introduced through the 20 valve 129 until it submerges the stators or rotors: This thoroughly impregnates them with the oil. They may be kept submerged in oil until ready to be assembled in the refrigerating system, thus preventing reabsorption of moisture.

25 The oil or lubricant with which the windings are impregnated preferably is similar to, or identical with, the oil or lubricant which is to be used permanently in the refrigerating system.

30 The treatment with the polar solvents, briefly described above, may include a drying operation. It also may include purification of the solvent for reuse. Thus after the stators and/or rotors have been placed on the spindles 100 through the door 150, they are rotated by means of the driving belts 151. A sufficient amount of heat is provided by means of the jacket 104, any solvent vapors driven off being collected in the reflux condenser 152 and draining through the pipe 153 to the sump 154. After the washing treatment has 35 been completed, the alcohol remaining in the drum 158 is drained into the sump 154 and thereafter air may be blown by the blower 155 through the heater 156 and through the hollow shaft 157 into and through the drum 158. The warm air thus introduced into the drum 158 comes in contact with the stators and removes the excess liquid from them before they are removed for treatment with the non-polar solvent.

40 The solvent gathered in the sump 154 may be purified by draining it through the valve pipe 160 into the still 161. Here heat is applied and the alcohol vapors are condensed in the condenser 104a. The condensate drains through the pipe 162 into the sump 163 for reuse, together with any additional supply of solvent which may be introduced into the sump 163 or independently into the drum 158. The solvent in sump 163 may be introduced into the drum 158 through the valve 164. Fig. 6 diagrammatically represents a 45 cross-section of the drum 158.

46 While I have disclosed embodiments and steps now preferred, it is to be understood that equivalent treatments or steps come within the scope of my invention. While I have disclosed treatment with two or more types of solvents, it is to be understood that a single solvent may be sufficient under certain conditions. Also, while I have disclosed the simultaneous removal of resins, waxes and oils with the removal of water, it is to be understood that such removal of water may

be dispensed with or may be performed in a different operation.

5 While the form of embodiment of the invention as herein disclosed, constitutes a preferred form, it is to be understood that other forms might be adopted, all coming within the scope of the claims which follow.

What is claimed is as follows:

1. The method of manufacturing a refrigerating system in which a sealed motor-compressor 10 unit has an electric motor in contact with the circulating agents of the system, which comprises treating the insulating windings of the motor prior to the charging of the system with a polar solvent and with a non-polar solvent to remove natural resins, waxes and oils, and thereafter charging the system with circulating agents 15 and sealing said system.

2. The method of manufacturing a refrigerating system in which a sealed motor-compressor 20 unit has an electric motor in contact with the circulating agents of the system, which comprises treating the insulating windings of the motor prior to the charging of the system with a polar solvent and with a non-polar solvent and heating 25 said windings to remove moisture and natural resins, waxes and oils, and thereafter charging the system with circulating agents and sealing said system.

3. The method of manufacturing a refrigerating system in which a sealed motor-compressor 30 unit has an electric motor in contact with the circulating agents of the system, which comprises treating the insulating windings of the motor prior to the charging of the system with a polar 35 solvent and with a non-polar solvent and heating said solvents and windings to remove moisture and natural resins, waxes and oils, and thereafter charging the system with circulating agents and sealing said system.

4. The method of manufacturing a refrigerating system in which a sealed motor-compressor unit has an electric motor in contact with the circulating agents of the system, which comprises treating the insulating windings of the motor 45 prior to the charging of the system with a hot solvent vapor and with a hot solvent liquid to remove moisture and natural resins, waxes and oils, and thereafter charging the system with circulating 50 agents and sealing said system.

5. The method of manufacturing a refrigerating system in which a sealed motor-compressor unit has an electric motor in contact with the circulating agent of the system, which comprises treating the insulation of the motor prior 55 to the charging of the system with a hot solvent to remove moisture and natural resins, waxes and oils, and thereafter charging the system with a circulating agent and sealing said system.

6. The method of manufacturing a refrigerating system in which a sealed motor-compressor unit has an electric motor in contact with the circulating agents of the system, which comprises treating the insulation of the motor prior to the charging of the system with a solvent to remove natural resins, waxes and oils, thereafter 65 impregnating the insulation with oil, and thereafter charging the system with a circulating agent and sealing said system.

7. A refrigerating system in which a sealed 70 motor-compressor unit has an electric motor in contact with the circulating agents of the system and in which the cotton electrical insulation of said motor has been treated, prior to the charging of the system, to remove natural resins. 75

8. A refrigerating system in which a sealed motor-compressor unit has an electric motor in contact with the circulating agents of the system and in which the cotton electrical insulation of said motor has been treated, prior to the charging of the system, to remove natural waxes. 5
9. A refrigerating system in which a sealed motor-compressor unit has an electric motor in contact with the circulating agents of the system 10 and in which the cotton electrical insulation of said motor has been treated, prior to the charging of the system, to remove natural resins, waxes and oils. 15
10. The method of manufacturing a refrigerating system in which a sealed motor-compressor unit has an electric motor in contact with the circulating agents of the system which comprises treating the insulating windings of the motor prior to the charging of the system to remove natural resins, and thereafter charging the system with the circulating agents and sealing said system. 20
11. The method of manufacturing a refrigerating system in which a sealed motor-compressor unit has an electric motor in contact with the circulating agents of the system which comprises treating the insulating windings of the motor prior to the charging of the system to remove natural waxes, and thereafter charging the system with the circulating agents and sealing said system. 25
12. The method of manufacturing a refrigerating system in which a sealed motor-compressor unit has an electric motor in contact with the circulating agents of the system which comprises treating the insulating windings of the motor prior to the charging of the system to remove natural oils, and thereafter charging the system with the circulating agents and sealing said 30 system.
13. The method of manufacturing a refrigerating system in which a sealed motor-compressor unit has the stator of the electric motor in contact with the circulating agents of the system 35 which comprises covering the windings of said stator with cotton electrical insulation, bringing said stator in contact with selective solvents adapted to remove natural resins from said cotton, charging said system with the circulating agents of the system and thereafter sealing said 40 system.
14. The method of manufacturing a refrigerating system in which a sealed motor-compressor unit has the stator of the electric motor in 45 contact with the circulating agents of the system which comprises covering the windings of said stator with cotton electrical insulation, bringing said stator in contact with selective solvents adapted to remove natural waxes from said cotton, placing said stator in said refrigerating system, charging said system with the circulating agents of the system and thereafter sealing said 50 system. 5
15. The method of manufacturing a refrigerating system in which a sealed motor-compressor unit has the stator of the electric motor in contact with the circulating agents of the system which comprises covering the windings of said stator with cotton electrical insulation, bringing said stator in contact with selective solvents adapted to remove natural oils from said cotton, placing said stator in said refrigerating system, charging said system with the circulating agents of the system and thereafter sealing said system. 10
16. A refrigerating system in which a sealed motor-compressor unit has an electric motor in contact with the circulating agents of the system and in which the circulating agents of the system flow through a relatively long capillary tube and in which the cotton electrical insulation of said motor has been treated, prior to the charging of the system, to remove natural resins. 15
17. A refrigerating system in which a sealed motor-compressor unit has an electric motor in contact with the circulating agents of the system and in which the circulating agents of the system flow through a relatively long capillary tube and in which the cotton electrical insulation of said motor has been treated, prior to the charging of the system, to remove natural waxes. 20
18. A refrigerating system in which a sealed motor-compressor unit has an electric motor in contact with the circulating agents of the system and in which the circulating agents of the system flow through a relatively long capillary tube and in which the cotton electrical insulation of said motor has been treated, prior to the charging of the system, to remove natural oils. 25
19. A refrigerating system in which a sealed motor-compressor unit has an electric motor in contact with the circulating agents of the system and in which the circulating agents of the system flow through a relatively long capillary tube and in which the cotton electrical insulation of said motor has been treated, prior to the charging of the system, to remove natural resins and oils. 30

FREDERIC L. CHASE.
